UNITED STATES PATENT OFFICE

130,199

DESIGN FOR A COMBINED BOTTLE, CLOSURE CAP, AND APPLICATOR

Hans J. Mamlok, New York, N. Y.; Margaret Mamlok executrix of said Hans J. Mamlok, deceased

Application December 14, 1939, Serial No. 88,897

Term of patent 7 years

To all whom it may concern:

Be it known that I, Hans J. Mamlok, a citizen of the German Reich, residing in the city of New York, in the county of New York and State of New York, have invented a new, original, and ornamental Design for a Combined Bottle, Closure Cap, and Applicator, of which the following is a specification, reference being had to the accompanying drawing, forming part thereof.

In the drawing:

Fig. 1 is a side elevational view of a combined bottle, closure cap, and applicator showing my new design;

Fig. 2 is a top plan view;

Fig. 3 a vertical sectional view.

I claim:

The ornamental design for a combined bottle, closure cap, and applicator, as shown.

HANS J. MAMLOK.
